SUPPORT OF WORKINGS IN UNDERGROUND
DEVELOPMENT

Emile Alfred Pierre, Valenciennes, France

Application March 17, 1948, Serial No. 15,364
In France March 20, 1947

13 Claims. (Cl. 61—45)

1

It is well known in underground development of mines that the roof close to the working face has to be kept up by overhung elements allowing a way to be kept clear for bringing a coal-cutting machine or scraper up to the face.

In the usual supports including suspended lengthening pieces kept up by one or more pit-props, the roof is no longer held up when the supporting arrangement is taken for using it ahead.

Plans have been put forward to cut out this inconvenience by making use of telescopic lengthening pieces but the latter in short only form a temporary support arrangement since a new lengthening piece always has to be put in the place of the former one when the latter is no longer effectively useful.

Speaking generally, all the arrangements put forward for eliminating these drawbacks call for the keeping in stock near the working face, of support parts intended for subsequent use and that, when laid on the floor of the levels, are in the way and always liable to go astray.

The supporting device according to the invention eliminates these various awkward points; in its essential features it is made up of a series of support members hinged together like links of a chain and incorporating locking means that enable each one of them to be fixed rigidly with the member ahead so that it may fit against the roof.

By making use of a sufficient number of these hinged members or links, there will be available a single support device, that is easy to carry, does not take up much room and is simple to work. With one of the central members wedged against the roof by a prop far enough away from the working face to allow room for the arrangements for removal of broken material, the next member ahead will be swung up against the roof, then clamped in this position. In the case where this particular link does not come up to the working face, the following link would be set up against the roof and locked.

The linking members located ahead of the previous ones therefore are hung down beforehand through their hinge joint against the working face so that they only have to be straightened up and locked as soon as there is room for them.

On the caving side, the corresponding links are unclamped in advance except the one nearest to the prop and when caving takes place these links swing and stay hanging through their hinges without any danger of being caught in the caved ground.

2

The links thus freed after caving may be disconnected from the neighboring links in a very simple manner, either one by one, or in sets and joined up to the idle links in front of the working face so as to be put in position as soon as they are wanted. The hinge joint connecting two neighboring links will be therefore preferably of a simple pattern so that these linking members may be taken apart and put up again without any trouble by ordinary underground labor.

The joint between the two links may be ensured in accordance with the invention either by removable pins going through corresponding holes bored in the supporting links, or by spindles fixed rigidly with certain links or with one end of the links and intended to engage with cradles carried by certain of the supporting links or by the end of each link opposite the one carrying the hinge pin.

20 In accordance with another characteristic feature of the invention, the supporting links show a male end and a female end planned to engage respectively with the female and male ends of paired links. Two sets of support links also may 25 be provided: the former containing two male ends and the latter two female ends.

The links include locking parts, for instance a hole and a key in the shape of a wedge, arranged so that their upper bearing surface may either be located in the plane of the bearing surface of the neighboring link, or form with the latter, above or below, a large enough angle, say 5° for instance, to take the shape of the corrugations of the roof without the necessity of inserting any intermediary packing.

In accordance with another feature of the invention, the supporting link members are connected to each other so as to form an endless chain of which the various component links are used successively at variable intervals and during an equally variable length of time, as a supporting link cooperating with the other links to form a single unit therewith through their being clamped together.

45 Such an arrangement that saves the miners the trouble of having to undo the hinge joint of the rear links to connect them up with the links hanging in front of the working face, assumes naturally enough that there is sufficient play in the hinges so as to enable the loose side of the chain of links to move aside from the vertical plane and to pass laterally of the prop.

50 My invention will be understood better with the help of the accompanying drawings given as an example and in which:

Fig. 1 is an elevational view of a supporting link according to the invention.

Fig. 2 is a plan view.

Fig. 3 is a section of it through line III—III of Fig. 1.

Fig. 4 is a section through line IV—IV of Fig. 1.

Fig. 5 is a section through line V—V of Fig. 1.

Fig. 6 is a section through line VI—VI of Fig. 1.

Figs. 7 and 8 show respectively in elevation and plan views two support links locked in the alignment with one another.

Fig. 9 shows in quite a diagrammatic way a timbering layout effected by means of a chain of supporting links in accordance with the invention.

The support link illustrated in Figs. 1 to 6 is made up of a main body having an I shaped cross section (Fig. 5) and formed by a web 11 provided in its upper portion with two symmetrical flanges 11b showing housings or hollowed out parts 12 planned to take projections rigid with the head of the prop.

The main web or body 11 is extended at one of its ends by a web 13 and at its opposite end by a yoke 14 strengthened by an outer flange 14a joined up with the flanges 11a and 11b of the main body and planned to take between its arms the end of the terminal web 13 of the paired link. The two arms of the yoke are connected at their lower end, that assumes the shape shown in Fig. 1, by a spindle 15.

In the two arms of the yoke are arranged two corresponding openings 16, 17, assuming together the shape of a wedge and strengthened by a peripheral flange 18 that merges at 19 into the flanges 14a.

The male terminal web 13 of the supporting link forms on the other hand, a lower hook 21 adapted to engage the spindle 15 carried by the yoke of the paired link and a wedge-shaped opening of suitable direction of taper capable of being positioned between and in register with the openings 16 and 17 of said yoke. A cross strengthening flange 13b connects up with the flanges 11a and 11b.

Figs. 7 and 8 show in elevation and plan views two supporting links S1, S2 similar to the one disclosed already and hinged together by means of the spindle 15 of link S1 and the hook 21 of element S2. The locking is effected by a key or wedge C that can take any intermediate position between positions C1 and C2 shown in dots and dashes in Fig. 8. In these two end positions the upper flanges 11a of the link S2 form with the corresponding portion of link S1 an angle of 5° directed either upwardly or downwardly. It will be understood that this latitude of wedging will enable in practice the support to be directly fitted against the roof notwithstanding the unevenesses of the latter.

Fig. 9 shows in quite a diagrammatic way a working fitted up with a supporting device in accordance with the invention and formed in this particular example by a chain of eleven links S1 to S11. The links S3—S10 fixed rigidly by keys constitute a continuous support carried by props E1, E2. On the carving side F, hang the two links S1 and S2 that, after being unkeyed, have swung down at the time of carving; while a link S11 hangs in front of the working face F1 close to which appears the removal carriage A. All that the miner has to do is to release the hinge spindle of the link S2 on the link S3 and to hinge on link S11 the link S1, thus freed and forming a unit with link S2. And so on step by step.

It will be advisable, of course, to hold up the support system thus formed by a fresh prop that will be set ahead of the prop E2 when the length of the overhang will be close to the safety limit.

5 In practice, the supporting links according to the invention and as shown in the accompanying drawings have a length of 35 cm. and a chain made up of six locked links with a length of about 2 meters carries an overhung load in the nature of four tons.

The links shown in Fig. 9 in dots and dashes correspond to the employment of an endless chain of links with cross play enabling the return side to pass laterally of the props E1, E2.

15 What I claim is:

1. A roof supporting system for a mine and the like working having a floor, a roof and a wall forming a working face, said support system including a continuous chain of connected supporting links for supporting the roof; a prop disposed on the floor at a selected distance from the wall and wedging at least one of the supporting links above the same against the roof; and locking means engaging the links which are located between the prop and said wall independently of the connections between said supporting links for holding the latter rigidly together in supporting position beneath said roof.

2. A roof supporting system for a mine and the like working having a floor, a roof and a wall forming a working face, said support system including a continuous chain of connected supporting links for supporting the roof; a prop disposed on the floor at a selected distance from the wall and wedging at least one of the supporting links above the same against the roof; and plural locking means engaging the links which are located between the prop and said wall independently of the connections between said supporting links for holding the latter rigidly together in supporting position beneath said roof.

3. A roof supporting system for a mine and the like working having a floor, a roof and a wall forming a working face, said support system including a continuous chain of connected supporting links for supporting the roof; a prop disposed on the floor at a selected distance from the wall and wedging at least one of the supporting links above the same against the roof; and plural locking means engaging the links which are located between the prop and said wall independently of the connections between said supporting links for holding the latter rigidly together in supporting position beneath said roof.

4. A roof supporting system for a mine and the like working having a floor, a roof and a wall forming a working face, said support system including a continuous chain of connected supporting links for supporting the roof; a prop disposed on the floor at a selected distance from the wall and wedging at least one of the supporting links above the same against the roof; and plural locking means engaging the links which are located between the prop and said wall independently of the connections between said supporting links for holding the latter rigidly together in supporting position beneath said roof.

5. A roof supporting system for a mine and the like working having a floor, a roof and a wall forming a working face, said support system including a continuous chain of connected supporting links for supporting the roof; a prop disposed on the floor at a selected distance from the wall and wedging at least one of the supporting links above the same against the roof; and plural locking means engaging the links which are located between the prop and said wall independently of the connections between said supporting links for holding the latter rigidly together in supporting position beneath said roof.

6. A roof supporting system for a mine and the like working having a floor, a roof and a wall forming a working face, said support system including a continuous chain of connected supporting links for supporting the roof; a prop disposed on the floor at a selected distance from the wall and wedging at least one of the supporting links above the same against the roof; and plural locking means engaging the links which are located between the prop and said wall independently of the connections between said supporting links for holding the latter rigidly together in supporting position beneath said roof.

7. A roof supporting system for a mine and the like working having a floor, a roof and a wall forming a working face, said support system including a continuous chain of connected supporting links for supporting the roof; a prop disposed on the floor at a selected distance from the wall and wedging at least one of the supporting links above the same against the roof; and plural locking means engaging the links which are located between the prop and said wall independently of the connections between said supporting links for holding the latter rigidly together in supporting position beneath said roof.

8. A roof supporting system for a mine and the like working having a floor, a roof and a wall forming a working face, said support system including a continuous chain of connected supporting links for supporting the roof; a prop disposed on the floor at a selected distance from the wall and wedging at least one of the supporting links above the same against the roof; and plural locking means engaging the links which are located between the prop and said wall independently of the connections between said supporting links for holding the latter rigidly together in supporting position beneath said roof.

floor and removably supporting one or more supporting links in said chain located above said props, said supporting links having lateral play therebetween in the pivotal connections thereof for allowing lateral shifting of the lower strand of the chain with respect to said props, and said supporting links also having transverse apertures which are independent of the pivotal connections of said supporting means and register mutually in substantially aligned position of the same supporting links; and locking pins for engaging in the registering apertures in any two adjacent connected links in order to secure the latter together to form a substantially rigid unit bearing against said roof.

5. A roof supporting system for a mine and the like working having a floor, a roof and a wall forming a working face, said support system including a plurality of connected supporting links forming a chain; a prop disposed on the floor at a selected distance from the wall and wedging at least one of the supporting links above the same against the roof; each link comprising a vertical web; a flange substantially perpendicular to the web and integral with the upper portion thereof and normally engaging against said roof; a shoe integral with the lower portion of the web disposed in a position to be engaged by the head of the prop; mutually overlapping ends upon each adjacent pair of supporting links; pivot members pivotally interconnecting the overlapping ends of said supporting links; and additional transverse members individually engaging simultaneously with any selected adjacent pair of said supporting links and locking the latter into a substantially rigid unit bearing against said roof.

6. A roof supporting system for a mine and the like working having a floor, a roof and a wall forming a working face, said support system including a plurality of connected supporting links forming a chain; a prop disposed on the floor at a selected distance from the wall and wedging at least one of the supporting links above the same against the roof; each link comprising a vertical web; a flange substantially perpendicular to the web and integral with the upper portion thereof and normally engaging against said roof; a shoe integral with the lower portion of the web disposed in a position to be engaged by the head of the prop; an integral male connecting member disposed at one end of each supporting link and a corresponding integral female connecting means disposed at the other end thereof; pivot means integral with the female connecting means on each supporting link and a corresponding integral pivoting engagement portion extending upon the male connecting member on each supporting link in effective position to pivotally engage and connect with the pivot means of the female connecting means on the next adjacent supporting link in the chain; and a plurality of securing means for independently and individually securing any selected pair of adjacent supporting links into a substantially rigid serial succession of links forming a unit independently of the pivotal connection between the links for bearing against said roof to support the latter.

7. A roof supporting system for a mine and the like working having a floor, a roof and a wall forming a working face, said support system including a plurality of connected supporting links forming a chain; a prop disposed on the floor at a selected distance from the wall and wedging at least one of the supporting links above the same against the roof; each link comprising a vertical web; a flange substantially perpendicular to the

web and integral with the upper portion thereof and normally engaging against said roof; a shoe integral with the lower portion of the web disposed in a position to be engaged by the head of the prop; an integral male connecting member disposed at one end of each supporting link and a corresponding integral female connecting means disposed at the other end thereof; a transverse spindle rigidly mounted on each female connecting means and a corresponding bearing formed upon each male connecting member and serving to pivotally engage with and carry the transverse spindle on the female connecting means of the next adjacent supporting link in the chain; and a plurality of securing means for independently and individually securing any selected pair of adjacent supporting links into a substantially rigid serial succession of links forming a unit independently of the pivotal connection between the links for bearing against said roof to support the latter.

8. A roof supporting system for a mine and the like working having a floor, a roof and a wall forming a working face, said support system including a plurality of connected supporting links forming a chain; a prop disposed on the floor at a selected distance from the wall and wedging at least one of the supporting links above the same against the roof; each link comprising a vertical web; a flange substantially perpendicular to the web and integral with the upper portion thereof and normally engaging against said roof; a shoe integral with the lower portion of the web disposed in a position to be engaged by the head of the prop; a male connecting member rigidly disposed at one end of each supporting link and a corresponding double female connecting means disposed at the other end thereof, the double female connecting means having a pair of substantially coaxial transverse bearing apertures upon each supporting link and the male connecting member on each of the latter having a corresponding bearing aperture registering with the coaxial bearing apertures in the female connecting means of the next adjacent link in the chain when the links involved are substantially aligned; removable locking members selectively inserted individually into the corresponding coaxial bearing apertures of the female connecting means and corresponding registering bearing aperture of the male connecting member in any selected adjacent pair of supporting links to lock the latter into a substantially rigid unit supporting said roof; and pivot means upon the supporting links independently interconnecting them pivotally in a continuous series of links forming said chain.

9. A roof supporting system for a mine and the like working having a floor, a roof and a wall forming a working face, said support system including a plurality of connected supporting links forming a chain; a prop disposed on the floor at a selected distance from the wall and wedging at least one of the supporting links above the same against the roof; each link comprising a vertical web; a flange substantially perpendicular to the web and integral with the upper portion thereof and normally engaging against said roof; a shoe integral with the lower portion of the web disposed in a position to be engaged by the head of the prop; a substantially flat integral extension upon one end of each supporting link and a corresponding opposite forked extension on the other end of each

link normally engaged by the flat extension of the next adjacent supporting link; means pivotally connecting the forked extensions upon the supporting links with the flat extensions on the respectively adjacent supporting links to connect them in a series to form the chain; and a plurality of securing means for independently and individually securing any selected pair of adjacent supporting links into substantially rigid serial succession of links forming a unit independently of the pivotal connection between the links for bearing against said roof to support the latter.

10. A roof supporting system for a mine and the like working having a floor, a roof and a wall forming a working face, said support system including a plurality of connected supporting links forming a chain; a prop disposed on the floor at a selected distance from the wall and wedging at least one of the supporting links above the same against the roof; each link comprising a vertical web; a flange substantially perpendicular to the web and integral with the upper portion thereof and normally engaging against said roof; a shoe integral with the lower portion of the web having transverse recesses; corresponding projections on the upper end of the prop for removably engaging in the recesses of the shoes of the supporting links; means for pivotally connecting one end of each supporting link to the other end of the next adjacent link in the series to form a continuous chain; and wedging means for independently locking at least two adjacent supporting links together into a substantially rigid unit for bearing against said roof.

11. A roof support system for mining and like galleries having a floor, a roof and a wall forming a working face, including a supporting chain for supporting the roof and having means for supporting said chain against said roof, said supporting chain including a series of similar supporting links, each of which supporting links comprises a main body of I-shaped intermediate cross-section and terminating in a bifurcated or double extension at one end thereof and terminating at the other end in a single web-shaped extension normally engaging between the two limbs of the bifurcated extension of the next ad-

- jacent supporting link in the chain; a transversely disposed spindle rigid with one extension and a transversely disposed hooked cradle rigid with the other extension for rockably engaging 5 and connecting with the spindle on the corresponding extension on the next adjacent link, the bifurcated extension on the one end of each supporting link having a pair of transversely aligned apertures in the two limbs thereof of suitable 10 tapered form of receiving a transverse wedge therethrough and the single wedge-shaped extension on the other end of the supporting link involved having a corresponding transverse tapered aperture registering with the two apertures 15 in the bifurcated extension of the next adjacent link when both adjacent links are disposed in a predetermined mutual roof supporting position with respect to each other; and a transverse wedge extending through the aligned and registering apertures in the corresponding adjacent extensions of the adjacent pair of supporting links and thereby holding both the latter together 20 in a rigid unit in said chain bearing against and supporting said roof.
12. A roof supporting system for a mine and the like having a floor and a roof, said support system including a chain of connected supporting links for supporting said roof; at least one prop adapted to be placed on said floor so as to 25 wedge at least one of said supporting links of said chain against said roof; and a plurality of locking means each adapted to hold a pair of consecutive supporting links rigidly together in supporting position beneath said roof.
13. A roof supporting system for a mine and the like having a floor and a roof, said support system including a plurality of supporting links for supporting said roof adapted to be connected 30 in series; at least one prop adapted to be placed on said floor so as to wedge at least one of said supporting links against said roof; and a plurality of locking means each adapted to hold a pair of consecutive supporting links rigidly together in supporting position beneath said roof
- 40 when said links are connected in series.
